THREE DIMENSIONAL PUZZLE

Wilbur H. Adams, 66 E. 83rd St.,
New York, N.Y. 10028

Filed Aug. 7, 1970, Ser. No. 24,361

Term of patent 14 years

Int. Cl. D21—01

U.S. Cl. D34—15

FIGURE 2

FIGURE 1

FIG. 1 is a perspective view of a three dimensional puzzle showing my new design, the undisclosed sides being similarly plain and unornamented; and

FIG. 2 is a fragmentary sectional view of one of the puzzle pieces which is representative of the depth thereof.

I claim:

The ornamental design for a three dimensional puzzle, substantially as shown and described.
